(57) CLAIM

I claim the ornamental design for a golf tee, as shown and described.

DESCRIPTION

FIG. 1 is a top plan view of a golf tee showing my new design;

FIG. 2 is a side view thereof, all sides being the same;

FIG. 3 is a view showing the profile of the golf tee along the central vertical plane; and,

FIG. 4 is a perspective view of the golf tee.

1 Claim, 1 Drawing Sheet

Side View (Identical from any position)
